1. A sheet holding device of improved construction, comprising a frame 10, comprising a bottom wall 11, an upstanding wall 12 and a channel-shaped upper wall portion 13 defined by a lower wall part 14 and an upper wall part 15 and a cross-head 16. Fashioned from the upstanding wall 12 centrally thereof is a rearwardly extending apertured flange 17 forming

an L-shaped projection or hook 18, the channel 13 being open at the rear and having a rearwardly extending flange 19, the flange 19 being apertured at 20 and 21, for free passage of a clamp screw 22 therethrough, the screw engaging a nut block 18.

Application March 8, 1949, Serial No. 80,151

5 Claims.

(Cl. 24—66)

1

This invention relates to devices for clamping a number of sheets together to support the same against relative shifting one with respect to the other. More particularly, the invention deals with a device of the character described, which may be secured to a suitable support or hung from a support in maintaining the secured or bound sheets in a predetermined position. The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a perspective view of a device made according to my invention.

Fig. 2 is a longitudinal sectional view through the device, as seen in Fig. 1.

Fig. 3 is a cross-section on the line 3—3 of Fig. 2; and

Fig. 4 is a section on the line 4—4 of Fig. 2.

My improved sheet holding device may be said to comprise a binder and is utilized primarily to support sheets on a surface or in a hung position to dispense with the need of conventional binders and, further, to dispense with the need of perforating sheets to adapt them for use in ring binders.

Quite often it is desirable to maintain a number of sheets which might comprise a file in gathered and secured relationship to each other for storage or predetermined positioning with respect to a support and it is the object of my invention to provide an elongated sheet holding device having means providing a clamping engagement with side edges of sheets in holding the same together and, in such manner, as to leave the major portion of each sheet exposed to be freely readable as and when desired.

In the accompanying drawing, I have shown one adaptation of my invention, in which a strip of metal is bent to form a supporting frame 10, comprising a bottom wall 11, an upstanding wall 12 and a channel-shaped upper wall portion 13 defined by a lower wall part 14 and an upper wall part 15 and a cross-head 16. Fashioned from the upstanding wall 12 centrally thereof is a rearwardly extending apertured flange 17 forming

2 ing hanger means, as and when the device is supported on a hanging hook, nail or the like.

Arranged between the walls 14 and 15 in the channel 13 centrally thereof is a nut block 18 fixed in position by indentures 19, note Fig. 2. The walls 14 and 15 are apertured, as seen at 20 and 21, for free passage of a clamp screw 22 therethrough, the screw engaging the nut block 18, as will be apparent.

10 The bottom wall 11 has extending end flanges 23, apertured as seen at 24, to receive screws or other fastenings for attachment to a backboard, table or other support, diagrammatically indicated by dot and dash lines at 25 in Fig. 1 of the drawing. The bottom wall 11 has, at its forward edge, an elongated bevelled lip 26, which provides free passage or entrance of a sheet or a series of sheets onto the upper surface of the wall 11. The wall 11 has longitudinal parallel grooves 27 on the upper surface thereof which work in conjunction with corresponding ribs 28 on a clamp bar 29 in firmly gripping and holding sheets held in the device against displacement therefrom.

20 The gripper bar is substantially the length of the lip flange 26 and upstanding wall 12 of the frame, as will clearly appear from Fig. 2 of the drawing, and this bar is supported on the lower end of the screw 22 through the medium of a coupling plate 30. The plate 30 is held on the bar by a pair of upstanding guide rods 31 arranged at the ends of the plate 30. The rods 31 pass snugly but freely through apertures 32, 33 in the walls 14 and 15, respectively. The plate 30 has a centrally upwardly bowed portion 34, in which is a keyhole aperture 35, the large portion of which is adapted to receive the head 36 at the lower end of the screw 22; whereas the reduced neck 37 of the screw fits snugly in the smaller part of said aperture so as to definitely couple the plate 30, as well as the bar 29, with the screw, while at the same time providing free rotation of the screw in the plate 30.

25 In other words, in assemblage, the head 36 is passed down through the larger part of the keyhole aperture 35 and the plate 30 is then moved to the right, as seen in the drawing, so as to engage the neck 37. Fixed to the screw 22 above and in spaced relation to the wall 15 is a milled-nut 38, forming a fingerpiece portion by means

of which the screw can be manually rotated. It will be apparent that the guide rods 31 maintain the projecting ribs 28 of the clamp bar 29 in vertical alinement or relationship with the grooves 27 of the bottom wall. It will also be noted that the edge of the bar, directly above the flange lip 26, is also bevelled, as seen at 39.

It will be apparent from a consideration of the device that, aside from the blanking and forming operations which are disclosed, in shaping the frame 10, the bar 29 and the plate 30 and the conventional operations of forming the remaining parts, the frame is simply bent to form the respective walls thereof, thus no complicated operations are provided in the construction of the parts. Therefore, devices of the kind under consideration can be produced very economically.

One of the distinctive advantages in a sheet holding device of the character described resides in the fact that no special operation is needed upon the sheets for the mounting or binding thereof, such for example as the perforation of sheets for ring binders. Furthermore, by utilizing sheet holding or binding devices of the character described, the sheets are readily accessible for examination and, in this examination, are retained against relative shifting or displacement one with respect to the other. It will be apparent that a long gripping engagement of the sheets is provided, thus further dispensing with rupture or tearing which is also experienced with other types of binders where the sheet is punctured, apertured or otherwise weakened at the edge portions thereof. Devices of the kind under consideration can also be utilized as a means for supporting sheet-like articles for hanging display, particularly where a firm engagement with the article is desirable.

Having fully described my invention, what I claim as new and desire to secure by Letters Patent is:

1. A device for retaining a plurality of sheets in assembled relationship to each other, said device comprising a frame having a bottom wall and spaced top walls integrally joining the bottom wall by a perpendicular back wall, the bottom wall having a bevelled edge facilitating guidance of sheets onto the upper surface of the bottom wall, an elongated clamp bar arranged between the bottom and top walls, spaced rods on said bar and operatively engaging the top walls to guide said bar and maintain alinement thereof with respect to the bottom wall, a bowed coupling plate secured to the top of the bar by said rods, a nut supported between the top walls, a screw engaging said nut, a head at the lower end of the screw engaging the bowed portion of the coupling plate in coupling the bar with said screw, and a fingerpiece on said screw to move the bar toward said bottom wall in clamping a plurality of sheets between said bar and bottom wall.

2. A device for retaining a plurality of sheets in assembled relationship to each other, said device comprising a frame having a bottom wall and spaced top walls integrally joining the bottom wall by a perpendicular back wall, the bottom wall having a bevelled edge facilitating guidance of sheets onto the upper surface of the bottom wall, an elongated clamp bar arranged between the bottom and top walls, spaced rods on said bar and operatively engaging the top walls to guide said bar and maintain alinement thereof with respect to the bottom wall, a bowed

coupling plate secured to the top of the bar by said rods, a nut supported between the top walls, a screw engaging said nut, a head at the lower end of the screw engaging the bowed portion of the coupling plate in coupling the bar with said screw, a fingerpiece on said screw to move the bar toward said bottom wall in clamping a plurality of sheets between said bar and bottom wall, and the bowed portion of said coupling plate having a keyhole aperture therein engaged by the head end of said screw for detachably coupling said screw with said strip.

3. A device of the character described, comprising a single sheet of material fashioned to form spaced bottom and top walls integrally joined by a perpendicular back wall, the top wall comprising a channelled portion, a nut supported centrally within the channelled portion, a perpendicular screw operatively engaging the nut, an elongated clamp bar arranged between said top and bottom walls, the screw having, at the lower end thereof, a neck portion, rods on said bar in spaced relation to the screw and operatively engaging the top wall to aline the bar in its movement in the frame, a coupling plate supported on the bar by said rods, said coupling plate having a bowed central portion with a keyhole aperture therein, said keyhole aperture engaging said neck portion in coupling the screw with said bar, and a fingerpiece portion on the screw beyond the top wall to actuate the same in movement of the bar toward and from said bottom wall.

4. A device of the character described, comprising a single sheet of material fashioned to form spaced bottom and top walls integrally joined by a perpendicular back wall, the top wall comprising a channelled portion, a nut supported centrally within the channelled portion, a perpendicular screw operatively engaging the nut, an elongated clamp bar arranged between said top and bottom walls, the screw having, at the lower end thereof, a neck portion, rods on said bar in spaced relation to the screw and operatively engaging the top wall to aline the bar in its movement in the frame, a coupling plate supported on the bar by said rods, said coupling plate having a bowed central portion with a keyhole aperture centrally thereof, said keyhole aperture engaging said neck portion in coupling the screw with said bar, a fingerpiece portion on the screw beyond the top wall to actuate the same in movement of the bar toward and from said bottom wall, and means providing gripper surfaces between the lower surface of the bar and the upper surface of said bottom wall.

5. A device of the character described, comprising a single sheet of material fashioned to form spaced bottom and top walls integrally joined by a perpendicular back wall, the top wall comprising a channelled portion, a nut supported centrally within the channelled portion, a perpendicular screw operatively engaging the nut, an elongated clamp bar arranged between said top and bottom walls, the screw having, at the lower end thereof, a neck portion, rods on said bar in spaced relation to the screw and operatively engaging the top wall to aline the bar in its movement in the frame, a coupling plate supported on the bar by said rods, said coupling plate having a bowed central portion with a keyhole aperture therein, said keyhole aperture engaging said neck portion in coupling the screw with said bar, a fingerpiece portion on the screw beyond the top wall to actuate the same in move-

ment of the bar toward and from said bottom wall, and outer edges of the bottom wall and bar being bevelled in opposite directions.
